RAIL ANCHOR

Rolandis A. Blair, Fort Wayne, Ind., assignor to
The P & M Company, Chicago, Ill., a corpora-
tion of Illinois

Application June 3, 1929, Serial No. 368,163

27 Claims. (Cl. 238—329)

My invention relates to rail anchors and has for one of its objects the provision of a new and improved rail anchor which will present certain advantages in connection with its manufacture and its application to a rail, and which when applied will maintain a firm grip on the top and bottom of the rail base and will be firmly locked in its applied position on the rail.

A more specific object is to provide an improved two-piece anchor which may be made from flat metal blanks and which blanks are so formed as to permit preliminary engagement of the members without distortion, but which, when fully assembled are maintained in their assembled relation by spring pressure exerted by one of the members.

Another object of the invention is to provide a rail anchor comprising a gripping member and a retaining member, the latter of which, when the anchor is applied to a rail, is flexed downwardly so that the resilient pressure resulting from said flexing of the member holds the gripping member turned about an axis longitudinally of the rail to force the upper and lower jaws into firm gripping engagement with the top and bottom surfaces respectively of one base flange of the rail.

The invention also contemplates as a specific construction, the wedging engagement between the gripping member and the retaining member, which insures a tight fit between said members and facilitates application of the anchor to a rail in substantially the same manner as though it were a one-piece device.

Other objects of the invention will be apparent from the detailed description of the preferred embodiment of the invention shown in the accompanying drawing.

In the drawing:

Fig. 1 is a side view of a rail anchor constructed in accordance with my invention applied to the base portion of a railroad rail, the said base portion of the rail being shown in section.

Fig. 2 is a plan view of the construction shown in Fig. 1.

Fig. 3 is a view in perspective of the rail gripping member, and

Fig. 4 is a view in perspective of the under rail portion or retaining bar of the anchor which is adapted to fit between the jaws of the member shown in Fig. 3.

The embodiment of the invention illustrated in the drawing consists, preferably, of a rail gripping member 10 for engagement with one base flange of the rail, and a retaining member

which extends across beneath the rail base and engages the opposite side thereof to lock the gripping member in its applied position. The gripping member 10 is formed from a flat metal blank bent to a U-shaped configuration to provide spaced flanges 12 and 13. The web 14 connecting the flanges of the member 10 is preferably cut away to provide a fulcrum seat 15 against which the retaining bar 11 bears when it is in its operative position. The vertical inner edges of the flanges 12 and 13 are each recessed to provide upper jaws 16—16a and lower jaws 17—17a for engagement with the top and bottom surfaces of the base flange. The distance between the upper and lower jaws of the rail gripping member is preferably such that the gripping member, in the absence of the under rail portion, may be readily applied to the rail base flange without the use of substantial driving force, this character of fit being adapted to permit said gripping member to be held turned slightly about an axis extending longitudinally of the rail when the anchor is in its normal applied position. The outer marginal portion of the flanges 12 and 13 are indented to provide inwardly projecting stop lugs 18—18a, for engagement with one end of the under rail portion or retaining member 11.

The under rail member 11 is formed at opposite ends with upstanding lugs 19 and 20. The lug 19 engages the vertical edge surface of one base flange of the rail. The other lug 20 engages the inwardly projecting lugs 18—18a of the rail gripping member when the retaining member is forced to its applied position between the flanges 12 and 13. The member 11 is normally straight so that, with the bottom surface bearing against the fulcrum seat 15 and the shoulder end 20 positioned in engagement with the lugs 18—18a, the other end of the bar will extend upwardly, as indicated in dotted lines in Fig. 1. With such construction it will be seen that the bar 11 will be flexed downwardly during the application of the device to the rail, that is to say, it will be flexed downwardly from the dotted line position shown in Fig. 1 to the position shown in full lines. It functions, therefore, as a resilient lever, which bears downwardly on the fulcrum seat 15 and upwardly against the inwardly projecting lugs 18—18a so as to hold the gripping member 10 turned about an axis 50 extending longitudinally of the rail.

The rotational movement of the gripping member forces the end portions of the upper jaws 16—16a into tight gripping engagement with the inclined top surface of the rail base at 55

the point 21 and also provides a tight grip of the bottom jaws 17-17a with the bottom of the rail base at the point 22.

The end of the retaining member is preferably formed to provide wedge surfaces 23 and 24 which, when the said bar is driven between the flanges 12 and 13, spreads the flanges apart. The reflex of the said flanges serves to clamp the retaining bar in its normally assembled position, whereby the anchor may be applied to the rail in substantially the same manner as a one-piece device. The wedge end of the bar 11, being somewhat wider than the shoulder end 19, facilitates assembling of the device in that the narrower end of the bar may be inserted between the flanges 12 and 13 and then forced to its operative position. The said bar may be moved to substantially the position shown in dotted lines in Fig. 2 before it is necessary to drive the wedge end between the flanges 12 and 13. The wedge end may be formed by any suitable method. I prefer, however, to shear the blanks from a bar of metal of uniform width and then, by a forging operation, displace the metal at one end of the blank to form the wedge surfaces.

By forming the anchor in two parts, one part may be made of a different quality of metal. For example, the bar 11 may be made of a higher quality of spring metal than the rail gripping member. A further advantage is presented by the above construction, in that the different sizes of anchors may be formed by merely varying the length of the retaining bar.

In operation the rail gripping member and the retaining bar are assembled by inserting the narrower end 19 of the bar 11 between the flanges 12 and 13 of the rail gripping member and then driving the bar in the direction of its length until the wedge end 23, 24, is tightly gripped between the flanges 12 and 13 of the gripping member and until the upstanding lug 20 on the bar is in engagement with the inwardly projecting lugs 18-18a of the gripping member. The upper jaws of the device may then be hooked over one flange of the rail base and the anchor as a whole driven transversely of the rail by striking the upstanding flange 20 of the retaining bar. The transverse movement of the anchor forces the end 19 of the bar downwardly and exerts a resilient leverage on the rail gripping member so as to rotate it in a clockwise direction, with reference to Fig. 1, so as to effect a binding grip of the upper and lower jaws at the points 21, 22 of the rail base. As soon as the anchor has been driven to its fully applied position, the locking shoulder 19 snaps over the opposite edge of the rail base so as to lock the gripping member in its fully applied position.

While I have illustrated my invention in connection with one specific embodiment, it will be obvious that modifications in structure might be made without departure from the spirit of my invention. Therefore, I wish it understood that I desire to claim both broadly and specifically all modifications in structure coming within the scope of the appended claims.

I claim:

1. A rail anchor comprising a jaw member recessed to receive one flange of a rail base with capacity for turning movement thereon, and separable resilient means for pressing upwardly against the bottom of the rail to exert pressure on said jaw member tending to turn it about an axis extending longitudinally of the rail; said separable means being movable lengthwise into

clamping engagement with said jaw member and held in clamped engagement therewith by reason of the resiliency of said jaw member.

2. A rail anchor comprising a jaw member recessed to receive one flange of a rail base with capacity for turning movement thereon, and separable means movable across beneath the rail into locking engagement with the opposite edge of the base and adapted to press upwardly against the bottom of the rail adjacent the last mentioned edge to exert pressure on said jaw member tending to turn it about an axis extending longitudinally of the rail; said separable means being movable lengthwise into clamping engagement with said jaw member and held in clamped engagement therewith by reason of the resiliency of said jaw member.

3. A rail anchor comprising a jaw member recessed to receive one flange of a rail base with capacity for turning movement thereon, and separable resilient means movable across beneath the rail into locking engagement with the opposite edge of the base and adapted to press upwardly against the bottom of the rail adjacent the last mentioned edge of the base to exert pressure on said jaw member tending to turn it about an axis extending longitudinally of the rail; said separable means being movable lengthwise into clamping engagement with said jaw member and held in clamped engagement therewith by reason of the resiliency of said jaw member.

4. A rail anchor comprising means for gripping one flange of a rail base, and a separable retaining member movable freely for a portion of its length relative to the gripping member but when fully assembled with the gripping member is held by spring pressure exerted by said gripping member and provided with a locking shoulder for engagement with the edge of the other flange of the rail base; the retaining member being positioned to exert pressure on the gripping member tending to turn it about an axis extending longitudinally of the rail.

5. A rail anchor comprising a rail gripping member having a pair of jaws for gripping the top surface of one base flange of the rail and a retaining member movable freely for a portion of its length relative to the gripping member but in its fully assembled position is held clamped by the spring action of said gripping member, movable transversely of the rail into locking engagement with the edge of the other base flange, and positioned to exert a rocking pressure on said gripping member to force the said jaws into tight gripping engagement with the top surface of the rail base.

6. A rail anchor comprising a rail gripping member provided with spaced jaw portions and a retaining member formed at one end with a wedge surface adapted to be driven into spring clamping engagement between said jaw portions and formed with a portion which, by engagement with the rail exerts lever pressure on said gripping member tending to rock it about an axis extending longitudinally of the rail.

7. A rail anchor comprising a rail gripping member provided with spaced jaw portions and a retaining member which increases in width toward one end to provide a wedge surface adapted to be forced by movement of the retaining member in the direction of its length into spring clamping engagement between the said jaw portions; the said retaining member being positioned to bear upwardly against the bottom surface of

the rail base so as to exert lever pressure on said gripping member tending to rock it about an axis extending longitudinally of the rail.

8. A rail anchor comprising a rail gripping

5 member provided with spaced jaw portions and a retaining member movable in the direction of its length into increasing spring clamping engagement between the jaw portions and held clamped therebetween by the resilient pressure exerted by said jaw portions and movable into locking engagement with the opposite edge of the rail base; the said retaining member being adapted to press upwardly against the bottom surface of the rail base and thereby exert a lever force 10 on said gripping member tending to rock it about an axis extending longitudinally of the rail base.

9. A rail anchor comprising a rail gripping member provided with spaced jaw portions for engagement with one base flange of the rail, and 20 a retaining member for holding the gripping member in its normal operative position on the rail comprising a metal bar extending across beneath the rail base, formed at one end with a shoulder for engagement with one edge of the rail base and formed at the other end with a wedge surface adapted to be forced between said jaw portions to spread the same and thereby effect a spring gripping action of the jaw portions 25 on said retaining member.

30 10. A rail anchor comprising a U-shaped rail gripping member having jaws for embracing the base of a rail at points spaced longitudinally of the rail with relation to each other, provided with a fulcrum seat and with a stop, a retaining member supported on said fulcrum seat and engaging said stop and adapted to press upwardly against said stop and against the bottom surface of the rail base to exert a turning pressure on said gripping member to force it into gripping engagement with the top and bottom surfaces of the rail base.

11. A rail anchor comprising a U-shaped gripping member, the flanges of which stand edge-wise to the edge of the rail base and are each 45 formed with recesses providing jaws for gripping the top and bottom surfaces of one base flange of the rail, a retaining member formed at one end with a locking shoulder for engagement with the longitudinal edge of the other base flange of the rail and formed at the other end with a lug movable into engagement with the gripping member to limit the transverse movements of said retaining member and provided also with a wedge surface for spreading said U-shaped member; the 50 said retaining bar being positioned to exert pressure against the bottom surface of the rail base and said gripping member, tending to rock the said gripping member about the extremity of the upper jaws as a fulcrum, to effect a strong lever grip of the device on the rail.

12. A rail anchor comprising means for gripping one flange of a rail base, and a retaining member movable in the direction of its length into increasing spring clamping engagement with said gripping member by reason of resilient pressure exerted by the gripping member and adapted to press upwardly against the bottom of the rail to exert pressure on the gripping member tending to turn it about an axis extending longitudinally 55 of the rail.

13. A rail anchor comprising a rail gripping member having a jaw for gripping the top surface of one base flange of the rail and a retaining member movable freely for a portion of its length relative to the gripping member but in its

fully assembled position has a spring clamping engagement with the gripping member by reason of resilient pressure exerted by the gripping member, movable transversely of the rail into locking engagement with the edge of the other base flange and positioned to exert a rocking pressure on said gripping member to force the said jaw into tight gripping engagement with said top surface of the base flange.

14. A rail anchor comprising a rail gripping 10 member having a pair of jaws for gripping the top surface of one base flange of the rail and a retaining member movable freely for a portion of its length relative to the gripping member but in its fully assembled position has a spring 15 clamped engagement by and between said jaws, movable transversely of the rail into locking engagement with the edge of the other base flange and positioned to exert a rocking pressure on said gripping member to force the said jaws into tight 20 gripping engagement with said top surface of said base flange.

15. A rail anchor comprising a rail gripping member provided with pairs of jaws for gripping the top and bottom surfaces of one base flange of 25 the rail and a retaining member movable freely for a portion of its length between said jaws into spring clamped engagement by said gripping member jaws, provided with locking means for engagement with the other base flange, and arranged 30 to press upwardly adjacent said locking means against the bottom of the rail to rock said jaws into gripping engagement with said base flange engaged.

16. A rail anchor comprising a rail gripping 35 member provided with spaced jaw portions and a retaining member movable in the direction of its length relative to the gripping member into spring clamping engagement with said jaw portions and clamped therebetween by the spreading pressure 40 exerted on said spaced jaw portions by said retaining member due to its aforesaid longitudinal movement and movable into locking engagement with the opposite edge of the rail base to hold the gripping member in its rail gripping position on 45 the rail.

17. A rail anchor comprising a rail gripping member provided with spaced jaw portions and a retaining member movable in the direction of its length relatively to the gripping member into 50 spring clamping engagement with the jaw portions and held clamped therebetween by the resilient pressure exerted by one of said members upon the other member due to the aforesaid relative movement of the members and movable 55 into locking engagement with the opposite edge of the rail base; the said retaining member being adapted to press upwardly against the bottom surface of the rail base and thereby exert a lever force on said gripping member tending to rock 60 it about an axis extending longitudinally of the rail base.

18. A rail anchor comprising a rail gripping member provided with spaced jaw portions and a retaining member movable in the direction of its 65 length relatively to the gripping member into spring clamping engagement between the jaw portions and held clamped therebetween by the resilient pressure exerted by the gripping member due to the aforesaid longitudinal movement of 70 said retaining member and movable into locking engagement with the opposite edge of the rail base; the said retaining member being adapted to press upwardly against the bottom surface of the rail base and thereby exert a lever force on said 75

gripping member tending to rock it about an axis extending longitudinally of the rail base.

19. A rail anchor comprising a rail flange gripping member having spaced jaw portions provided with angularly disposed surfaces and a retaining member movable in the direction of its length into increasing spring clamping engagement with said angularly disposed surfaces, whereby said members are held engaged by reason of the resilient pressure exerted by the jaw portions of said gripping member.

20. A rail anchor comprising a rail flange gripping member and a retaining member movable in the direction of its length relative to said clamp member and into locking engagement with the opposite flange of the rail base to hold said gripping member in its applied position on the rail, one of said members having a cam surface engageable by the other and providing a spring pressure engagement of the clamp member jaws on opposite longitudinal edges of the retaining member.

21. A rail anchor comprising a rail flange gripping member having spaced jaw portions provided with angularly disposed surfaces, and a retaining member movable freely between said jaws for a portion of its length during the assembly of the parts but in its fully assembled position has a spring clamping engagement with said angularly disposed surfaces of said clamp member jaws whereby the said gripping member and said retaining member are held engaged by resilient pressure exerted by said jaw portions on opposite longitudinal edges of the retaining member.

22. In a two part rail anchor, the combination of an abutment plate member provided with oppositely disposed spaced bearings, and a transverse bar adapted by wedging engagement of its longitudinal edges with said bearings when the device is on a rail to hold said abutment plate member in position on the rail and adapted by said engagement with said bearings when the device is free of the rail to hold said gripping member and retaining member engaged with each other.

23. A rail anchor comprising a pair of relatively movable gripping members adapted to grippingly embrace a rail base between them and positioned,

relative to one another when separate from a rail, in readiness for application to a rail, one of said members being in embracing engagement with the other member and exerting holding pressure on the other member in a plurality of non-parallel directions, the said members being in close frictional engagement and constitute, in effect, a unitary structure for application to a rail.

24. A rail anchor comprising a pair of relatively movable rail gripping members, one of which is formed with converging surfaces between which the other member is wedgingly engaged when the anchor is separate from a rail, said surfaces being so disposed as to hold the members relatively to one another in positions of readiness for assembly to a rail.

25. A rail anchor comprising a pair of relatively movable rail gripping members, one of which is formed with converging surfaces between which the other member is wedgingly engaged when the anchor is separate from a rail, the compressive forces resulting from such engagement being exerted in lines which will extend longitudinally of a rail when the anchor is applied thereto.

26. A rail anchor comprising a pair of relatively movable rail gripping members, one of which is formed with converging parts between which the other member is wedgingly engaged with flexion of said converging parts when the anchor is separate from a rail, whereby the reflex action of said flexed member maintains such frictional engagement of the members that they are held in firm frictional engagement for application as a unit to a rail.

27. A rail anchor comprising a pair of relatively movable members, adapted to grippingly embrace a rail base between them, said members being so formed and correlated that upon predetermined relative movement, when separate from a rail, the members enter into frictional engagement the intensity of which increases with the amplitude of said relative movement to the extent that the members are in such close frictional engagement with one another as to be, in effect, a unitary device for application to the rail base.

ROLANDIS A. BLAIR.
